United States Patent Office.

BENJAMIN BEST, OF DAYTON, OHIO, ASSIGNOR TO HIMSELF AND LONDON MARTS, OF THE SAME PLACE.

Letters Patent No. 66,286, dated July 2, 1867.

IMPROVED SCAFFOLD.

The Schedule referred to in these Letters Patent and making part of the same.

TO ALL WHOM IT MAY CONCERN:

Be it known that I, BENJAMIN BEST, of Dayton, in the county of Montgomery, and State of Ohio, have invented a new and improved Scaffold; and I do hereby declare that the following is a full, clear, and exact description thereof, which will enable others skilled in the art to make and use the same, reference being had to the accompanying drawings, forming part of this specification, in which—

Figure 1 is a perspective view of my improved scaffold.

Figure 2 is a side view partly in section of the same.

Similar letters of reference indicate like parts.

This invention relates to a new scaffold, which consists of a series of upright posts, which are anchored to the ground by means of braces, and on which sliding braces for supporting the platform are arranged in such a manner that the latter can be raised and lowered at will by the parties on the platform. The length of the scaffold can be regulated by the number of uprights employed.

A A' are upright posts, the lower end of each of which is secured to a sill, *a*, which is steadied by a brace, *b*. This brace where it is attached to the post is perforated by a number of holes, so that the position of the sill may be changed to adapt it to uneven ground. Three (more or less) braces *c c* are pivoted to the sides of each post A A' in such a manner that by their use the said posts can be firmly anchored into the ground, as is clearly shown in fig. 1. On the front of each post, *i. e.*, on that side of the same which faces the side of the building or wall on which the scaffold is to be used, is arranged a sliding bar, *B*, on which one or more clips *d* made of sheet metal or other suitable material are arranged, so as to surround the post A A'. On the bar *B* are also arranged two ears or lugs *e e*, which may be made in one piece with the clip *d*, in which lugs are the bearings for the shaft *f* of a drum, *C*, and ratchet-wheel *D*. To the drum is secured the end of a cord, *h*, of which the other end is fixed to the bar *B*, and which cord passes over a pulley, *E*, arranged on the top of the upright A or A', as is clearly shown in the drawing. By turning a crank, *g*, which is secured to the end of each shaft *f*, the cord *h* is either wound around the drum or unwound from the same, thereby raising or lowering the bar *B* as may be desired. By a spring-catch, *i*, which is pivoted between two lugs *k*, near the lower end of the bar *B*, and which fits into holes *l l* which are provided in the post A or A', the bar *B* is held in position, and can only be raised or lowered by releasing this spring-catch. A pawl, *m*, which is hinged to the side of the bar *B*, catches into the teeth of the wheel *D* and prevents the bar *B* from moving down on the bar A or A', so that for elevating the bar *B* the spring-catch *i* is only to be released, and the cord *h* wound upon the drum. But for lowering the bar *B* the spring-catch *i* and the pawl *m* must be released. To the sides of each bar *B* are pivoted two horizontal arms *F F*, and two vertical suspended arms *G G*, the respective ends of which are connected by a brace, *H*, as is clearly shown in the drawing. To the front of the horizontal arms is secured a friction-roller, *n*, which touches the wall, in front of which the scaffold is erected. The arms *F F* of the post A' are bridged over by a plate, *o*, to the edges of which the planks *I I* are hinged, which serve as a platform, when placed upon the arms *F F* of the posts A. The ends of these planks are then firmly secured to the arms *F F* by means of cords *p*, pins *q*, or otherwise. The crank *g* is arranged at a convenient height above the platform *I*, so that it may be easily handled by the parties standing on the platform. It is evident that this scaffold can be easily folded up and packed into a comparatively small space.

What I claim as new, and desire to secure by Letters Patent, is—

1. The combination of the uprights A A', pivoted and adjustable braces *b* C, pivoted sliding and supporting frame *B F G H*, friction-rollers *n*, clip *d*, with its appendage, pivoted spring-catch *i*, hinged planks *I*, pulleys *E* and cord *h*, operating in the manner described for the purpose specified.
2. The clip *d* when made in one piece with the lugs *e*, so that it serves to guide the supporting frame on the upright, and to hold the windlass for raising and lowering the said supporting frame, as set forth.
